UNITED STATES PATENT OFFICE.

WILLIAM JONATHAN KEYS, OF YORK HILL, LOUGHTON, ENGLAND.

DESIGN FOR A BUTTON-HOOK.

SPECIFICATION forming part of Design No. 20,160, dated September 23, 1890.

Application filed June 4, 1890. Serial No. 354,295. Term of patent 7 years.

To all whom it may concern:

Be it known that I, WILLIAM JONATHAN KEYS, clerk, a subject of the Queen of Great Britain, at present residing at York Hill, 5 Loughton, in the county of Essex, England, have invented and produced a new and original Design for Button-Hooks, of which the following is a specification, reference being had to the accompanying drawing, forming 10 part thereof, and in which the improvement is shown in side elevation.

The design of this button-hook has the following characteristic features: The shank *a* of the instrument is bent at a short distance

from the hook *b* until the part *a'* is at a right angle to the main part *a* of the shank and the hook *b* is in a plane about perpendicular to the part *a*.

I claim—

The design for a button-hook, herein shown and described.

WILLIAM JONATHAN KEYS.
